UNITED STATES PATENT OFFICE

151,669

DESIGN FOR A ROTOR PLANE

Joseph Youhouse, Fairfield, Conn.

Application October 7, 1946, Serial No. 133,806

Term of patent 7 years

(Cl. D71—1)

To all whom it may concern:

Be it known that I, Joseph Youhouse, a citizen of the United States, residing at Fairfield, in Fairfield County, and the State of Connecticut, have invented a new, original, and ornamental Design for a Rotor Plane, of which the following is a specification, reference being had to the accompanying drawing, forming part thereof.

Fig. 1 is a top plan view of a rotor plane, showing my new design;

Fig. 2 is a front elevational view thereof;

Fig. 3 is a side elevational view thereof; and

Fig. 4 is a side elevational view with the wings in a rotating position, as when at 90° to Fig. 3.

I claim:

The ornamental design for a rotor plane, substantially as shown.

JOSEPH YOUHOUSE.
